UNITED STATES PATENT OFFICE.

ALFRED OWEN CROZIER, OF NEW YORK, N. Y.

MACHINE AND METHOD OF MAKING CEMENTITIOUS PRODUCTS.

1,385,864.

Specification of Letters Patent. Patented July 26, 1921.

Application filed April 12, 1920. Serial No. 373,065.

To all whom it may concern:

Be it known that I, ALFRED OWEN CROZIER, a citizen of the United States of America, residing at New York, in the county and State of New York, have invented certain new and useful Improvements in Machines and Methods of Making Cementitious Products, of which the following is a full, clear, and exact description.

- 10 This invention relates to the manufacture of cementitious articles, more especially concrete pipe and solid or hollow sections for building posts or columns and for turning out such articles rapidly and economically, 15 preferably using "slush" or wet concrete for the purpose. By the term "slush" or wet concrete as herein used is meant a mixture of hydraulic cement, sand or other suitable inert material, and water in excess of the 20 amount required for complete hydration of the cementitious ingredient. To this and other ends the invention consists in the novel features of construction and combinations of elements hereinafter described.
- 25 More particularly the invention relates to the so-called column method of making hollow concrete articles, by removing successive sections from one end of a tubular column. For this purpose I provide an outer sup- 30 porting element in the form of an upright hollow shaft or container and inside thereof an inner supporting element in the form of an upright core. In the annular space thus provided between the two supporting 35 elements the wet concrete is deposited, forming a tubular column of cementitious material. The weight of the column thus produced helps to compact and unwater its lower portion, to an extent which depends 40 somewhat upon the height of the column. Preferably its height is such that the products removed from the lower portion will be dense enough, and sufficiently unwatered, to be self-sustaining without lateral support, 45 though unset; that is, stiff enough to stand alone without being deformed by its own weight.

When solid round sections are desired the inner element or core is left out and not 50 used.

Below the hollow shaft or container is a pallet upon which the column of cementitious material rests. Means is provided for effecting a relative movement of the pallet 55 and one or both of the column supporting elements whereby the column descends with-

out the container in position to be severed and afterward removed from the machine. After the severing of the lower end of the column to permit the withdrawal of the 60 complete article, the severing means serves to retain the column within the container until such time as the pallet is in position to again receive and support the column. After one article has been completed and 65 removed the cycle of operations is repeated, additional concrete of variable consistency being added from time to time to maintain the column at the desired height.

In order to facilitate the descent of the 70 column and also to improve the surface of the completed article means is provided for effecting a relative vertical movement of one or both of the supporting elements and preferably for also effecting a rotational 75 movement of one or both of said elements during certain preferred periods in the operation of the machine.

These features are of the utmost importance and will be referred to in more detail 80 hereafter.

Means is also provided for changing the length of article without the necessity of a separate machine for each size to be produced.

85 The preferred embodiment of the invention is illustrated in the accompanying drawings in which:

Figure 1 shows a side elevation of the machine with the pallet and core in lower 90 position prior to the severing of the lower section of the cementitious column.

Fig. 2 is a detail sectional view of certain parts of the machine showing particularly the means for supporting the core and shaft 95 so as to permit the rotation thereof.

Fig. 3 is a view similar to Fig. 1 but with certain parts omitted. This view shows the lower section severed by the knives and slightly lowered to free the section from 100 the annular ring below the knives. The core is shown in upper position.

Fig. 4 shows the pallet and table raised into proximity to the lower end of the shaft and certain of the control mechanism in position to disconnect the elevating mechanism from the source of power.

Fig. 5 shows the knives withdrawn and the pallet in elevated position with the parts moving to a position to lower the pallet and 110 table.

Fig. 6 is a view similar to Fig. 5 but

with the parts moved to a further extent so as to release the lower table and permit it to descend.

Fig. 7 is a detail view showing the table 5 and the mechanism for depressing it.

Fig. 8 shows a top plan view of the machine.

Fig. 9 is a detail sectional view taken on line 9—9 of Fig. 1.

Fig. 10 is a detail sectional view taken 10 on line 10—10 of Fig. 1.

Fig. 11 is a detail sectional view taken on line 11—11 of Fig. 1.

Fig. 12 is a detail view taken on line 15 12—12 of Fig. 1.

The machine comprises a base 15 to which is bolted suitable upright frame members 16 secured at their upper ends to a framework 17 and intermediate their ends to an 20 intermediate framework 18. The framework 17 forms a support for an element in the form of a hollow shaft or container for a column of unset cementitious material. This container 19 is preferably fastened to 25 a hopper member 20 which member carries a worm wheel 21 having a suitable bearing between the wheel and framework to permit the rotation of the hollow shaft (see Fig. 2). Within the hollow shaft element 30 19 is an upright tubular core 22 which forms an element for supporting the interior of the unset cementitious column and for shaping the column into tubular form. The core element at its upper end is fastened to 35 a sleeve having a concentric plate 23 integral therewith. Fastened to this plate by suitable bolts is a circular ratchet plate 24 (best shown in Fig. 10). Above the ratchet plate 24 is a head plate 25 which is secured 40 to plate 23 by embracing collars 26 which permit relative rotational movement of the head plate and core but which cause the core to be raised in unison with the lifting of head plate 25. The collar members are 45 provided with a suitable pin which engages a cam slot 27 and also are provided with spring pressed pawls 27^a engaging the ratchet plate 24 (see Fig. 10). The parts just described are adapted to effect a rotational movement of the core upon the lifting of the head plate and also permit the descent of the core without rotation as will readily be understood. Below plate 23 and fastened to the core is a cross arm 28.

55 In order to effect the rotation of the hollow shaft or container I provide a worm 29 which meshes with wheel 21. The shaft upon which the worm wheel is mounted is driven by a chain 30 from an upper sprocket 60 31 which is adapted to be driven in unison with a shaft 32 by means of a clutch 33. The rotational movement of the hollow shaft is effected at a certain time in the operation of the machine when the cementi-

tious column is descending as will hereafter 65 be pointed out.

The rotation of the hollow shaft and the core is adapted to trowel the surface of the column and draw neat cement and water to the surface. The surface thus produced is 70 hard, dense and smooth surface which is particularly desired in most of the finished articles. The surface is also more or less troweled, by sliding the column intermittently in its contact with the core and shaft. 75

In addition to the troweling action which improves the surface, the drawing of the water to the surface facilitates the descent of the unset cementitious column from the hollow shaft and the withdrawal of the core 80 from the column. The water acts as a lubricant between the mass of cementitious material and the shaft or core and minimizes the sticking of the particles of cement thereto.

85 In order to elevate and lower the core at suitable times in harmony with the movements of other parts of the machine the head plate 25 is provided with a pair of pivoted dogs spring pressed or pawls 33^a which, 90 when the core is in lower position, engage over the upper surface of a cross head 34 which is guided by fixed vertical guide rods 35. These same guide rods also guide the cross arm 28 in its up and down movement. 95 Fastened to the cross head is a vertical screw 36 which at its upper end is threaded in a worm wheel 37 which meshes with a worm 38 (see Figs. 2 and 8.) This worm wheel is fast upon shaft 32 and also fast to this shaft 100 are gears forming elements of independent gear trains 39 and 40. A driving shaft 41 having a suitable belt pulley is provided with clutch members 42 and 43 adapted to be engaged with either one or the other of the gear trains and moves them in unison with the driving shaft 41. These clutch elements are shifted by a suitable shifter shaft 44 which also operates the clutch 33 for effecting the rotation of the hollow shaft. 110 The gear trains 40 and 39 have differing numbers of gears whereby one train drives the worm 38 in one direction and the other in the opposite direction and thereby lowers or elevates screw 36 and cross head 34 attached thereto.

115 Assuming the parts in the position shown in Fig. 1 with the end of the unset column projecting from the lower end of hollow shaft 19 as shown and with the core element in lower position.

To raise the core and effect the severing of the lowermost section of the cementitious column, the operator grasps handle 45 and depresses it to the dotted line position 120 shown in Fig. 1. Handle or lever 45 through slotted link 46 draws down the control rod 47 and shifts shifter shaft 44 to the

right engaging clutch 43. The power then rotates the various shafts, gear trains and worm gearing to elevate screw 36 and cross head 34 attached thereto. Inasmuch as the dogs 33^a are engaged, the head plate 25 and core element 22 will be raised. Concurrently with the raising of the core, it is rotated by the means previously described, so as to trowel the interior surface of the tubular cementitious column and loosen the contact between the core and column. The core continues to move upwardly until the dogs 33^a contact against stops 49 which disengage them from cross head 34 and permit the core element to come to rest. Concurrently with the disengagement of dogs 33^a a pivoted dog 50, carried by cross head 34, engages a stop 51 on the control rod 47 lifting the rod and thereby disengages clutch 43 which brings the parts of the machine to a standstill.

The severing of the lower section is effected preferably during the raising of the core. Knives 52 are interconnected by a link-work including intermeshing gear segments 53. By the elevating of the segment arms the knives are forced into the cementitious material between the end of the hollow shaft 19 and the top of an annular ring 54 which forms a support for the knives. Fastened to rock shaft 55, to which the segment arm is keyed, is an arm 56 to which a rod 57 is connected by spring connection 58. Rod 57 is guided for vertical movement by suitable brackets fastened to frame member 16 and the upper end of the rod has a turned-over end forming a hook 59. This hook 59 is adapted to engage a projection 60 from cross-head or arm 28 during the upward movement of that arm, thereby elevating rod 57 and compressing a coil spring 61. This movement of rod 57 elevates the intermeshing segments and forces the knives through the unset concrete until they contact with the core. Thereafter the spring connection 58 yields and after the lower end of the core has passed the plane of the knives this spring tension at 58 causes the knives to move further inward to completely sever the cementitious column and preferably around the lower end of the core. The knives are preferably recessed to embrace the core.

In order to remove the completed and severed article it is necessary to lower the article slightly to the position shown in Fig. 3 in order to clear the upper part of the article from the ring 54. The means for thus lowering the severed article will now be described.

The article rests upon a pallet 63 which is supported by a table 64. This table is carried by vertical rods 65. Springs 66 are interposed between the rods and the table 65 to permit the table to be moved slightly relative to the rods.

To depress the table the operator pulls a lever 67 (see Fig. 7) mounted on a shaft 68 which is journaled in base 15. To this shaft is keyed a curved tongue or camming member 69 which is adapted to enter a slot in a rod 70 which extends downwardly from the table 64. The engagement of these parts depresses the table against the tension of the springs 66 sufficiently to permit the article to clear the ring 54 and be removed from the machine. To retain the table in lower position I provide a pawl and ratchet device 72 which may be tripped by the foot of the operator. Thereafter the table returns to normal position and the handle or lever 67 returns under the influence of a coil spring 73.

After the removal of the completed article a new pallet is placed upon the table 54 and it is necessary that the table and pallet be raised into the position shown in Fig. 4. To do this I disengage the dog 50 from stop 51 by means of a small lever 75 which actuates a bell crank 76 connected to a rod 77 swung at its upper end on a link 78. Pressing down on lever 75 swings the rod to the dotted line position shown in Fig. 1 and as the rod 77 passes through an aperture in the tail of dog 50, this dog is swung to clear stop 51. Thereafter the lever 45 can be depressed a second time engaging clutch 43 and elevating screw 36 and cross head 34 attached thereto. Up to this time the ends of the cross head have slid freely along rods 65. Additional upward movement of the cross head brings it into contact with the adjustable stop nuts 65^a on the top of rods 65. Thereafter the rods are drawn up elevating the table and bringing the pallet into close relation with the lower edge of annular ring 54. Eventually a stop member 80 which rests on top of cross head 34 slides along rod 35 until it contacts with a collar 81 on control rod 47 (see Fig. 4). The control rod is then lifted thereby declutching clutch 43 and bringing the machine again to a standstill. During the movement of the control and clutch parts springs 66 permit the upward movement of cross head 34 without imposing undue strain upon the table.

The next steps in the operation of the machine are the restoration of the knives to outer position, the lowering of the core and the concurrent lowering of the table 120 and pallet.

Before the core can be lowered the cross head 34 must be lowered from the position shown in Fig. 4 to that shown in Fig. 5. During this movement of the cross head the table 64 is retained in upper position by pivoted pawls 82 which engage notches 82^a in the rods 65 (see Figs. 4 and 5). To effect the lowering of cross head 34 the handle or lever 45 is raised to dotted line po-

sition (Fig. 4) thereby engaging the lower-
ing clutch 42 as shown in Fig. 5 and caus-
ing the screw and the attached cross head
to descend.

5 The lifting of the lever 45 also through
slotted link 83 rocks a sleeve 84 which is
splined to rod 57 and thereby rotates the
rod so as to free the hooked end 59 from
the camming abutment 60. Rod 57 is then
10 forced down under the influence of the
compressed coil spring 61 thereby with-
drawing the knives to the outer position as
shown in Fig. 5. A suitable torsion spring
85 restores the hook end 59 to such posi-
15 tion as to properly reengage over the abut-
ment 60 when cross arm 28 is lowered. The
slot in link 83 permits the handle 45 to be
depressed without releasing the knives.

Cross head 34 contacts with head plate 25,
20 the pawls 33^a reengage cross head 34 and
thereafter the core 22 moves downwardly in
unison with the cross head (see Fig. 6).
During the lowering of the core means is
provided for lowering the table 64. The
25 knives 52 which previously supported the
unset cementitious column having been
withdrawn, the cementitious column de-
scends in unison with the lowering of the
table and since clutch 33 is engaged simul-
30 taneously with the engagement of clutch 42,
the container or shaft 19 is rotated thereby
drawing neat cement and water to the sur-
face of the unset cementitious column, there-
by troweling the surface and lubricating the
35 same so that the cementitious column slides
freely out of the lower end of the shaft.

When the cross head descends to the posi-
tion shown in Fig. 6 the cam shaped ends 85
of the cross head contact against the cam
40 surfaces 86 of pawls 82 and disengage the
pawls from the notches in rods 65 and there-
by permit the downward movement of the
same and the table 64 carried thereby. To
45 prevent the table descending too rapidly I
provide notches 87 in the inner sides of the
rods into which pivoted spring tensioned
pawl members 88 engage so as to support
the rods 65 from the cross head (see Figs. 6
50 and 9). After these pawl members are en-
gaged the rods 65 descend in unison with the
cross head and the table 64 descends. The
descending movement continues until such
time as the cross bar 28 contacts with a stop
55 collar 89 on the control rod 47 to thereby
lower the control rod and disengage clutches
42 and 33 and bring the parts to a stand-
still. The machine is now in the position
shown in Fig. 1. It will be obvious that
60 means must be provided for disengaging the
pawl members 88 from the notches 87 in the
rods 65. Otherwise in the next cycle of op-
erations the table 64 would be drawn in uni-
son with the drawing up of the core. In
65 order to prevent such action I provide cam
block 90 attached to the frame members of

the machine which are adapted to contact
with the pawl members 88 and withdraw
the same from the notches.

It is also desirable that a means be pro-
vided for preventing the dropping of the
70 core when in upper position. This may be
accomplished either by having the knives 52
pass under and support the core or by pro-
viding tapered and adjustable friction plugs
75 91 in cross bar 28 which plugs frictionally
engage the guide rods 35 and prevent the
free descent of the core.

The cycle of operations heretofore de-
scribed is now repeated, additional quanti-
ties of slushy concrete being added from
80 time to time to hopper 20.

If it is desired to make articles of differ-
ent lengths—*i. e.*, shorter than those illus-
trated, this may be done by the setting of
the stops on control rod 46 by shortening
85 the distance between notches 82^a and nuts
65^a by adjusting these nuts on rods 65. The
brackets which support shaft 68 in the base
must be raised and a new rod 70 of proper
90 length must be provided. Also, the knife-
actuating rod 57 must be replaced by an-
other of proper length.

It is important to note that this method
does not depend wholly upon the weight of
95 the concrete in the column to compact or
densify and unwater the concrete of the
lower part of the column and render it rela-
tively self-sustaining when cut off in sec-
tions that are to be the desired products.
100 The effect of confining such "slush" con-
crete between the core and supporting shaft
or container, and alternately repeatedly ro-
tating such shaft and core is to "work" or
"knead" or manipulate such concrete and
105 thus readjust the various solid particles
thereof and compact and fit them more
snugly together and concurrently expel from
the interior of the concrete mass toward its
surfaces the excess portion of the water
110 therein. It should be noted that there is
considerable troweling effect obtained by
the sliding of the column intermittently in
contact with the core and container shaft
even when neither the core nor shaft is ro-
tated.

Certain of the features of the present in-
vention are claimed broadly in my copending
application Serial No. 373,064, filed April
12, 1920.

While I have particularly described the
120 forming of hollow articles, it is to be under-
stood that solid columns can also be formed
by omitting the core element.

What I claim as my invention is par-
ticularly set forth in the appended claims.

I claim:

1. In a machine for making hollow con-
crete articles, in which such articles are
formed by removing successive sections from
the lower portion of an intermittently de-

ing the other element to permit the descent of the tubular column, means for limiting said relative movement of the pallet and said element after the column has descended 5 to a predetermined point, and means for severing the lower end of the column.

9. In a machine for making hollow concrete articles, in which such articles are formed by removing successive sections from 10 the lower portion of an intermittently descending unset cementitious column of tubular form maintained between inner and outer upright elements, in combination, an outer shaft element, an inner core element, a pallet 15 for supporting said tubular column of cementitious material, means for effecting a relative vertical movement of the pallet and one of the elements and concurrently lowering the other element to permit the descent 20 of the tubular column, means for limiting said relative movement of the pallet and said element, means for severing the lower end 25 of the column, and means for effecting a second relative movement of the pallet and one of said elements to bring the parts in position to permit the second descent of the tubular column.

10. In a machine for making hollow concrete articles, in which such articles are formed by removing successive sections from 30 the lower portion of an intermittently descending unset cementitious column of tubular form maintained between inner and outer upright elements, in combination, an outer shaft element, an inner core element, a pallet 35 for supporting said tubular column of cementitious material, means for lowering said pallet with respect to one of said elements to permit the descent of the tubular column, 40 means for severing the lower section of the column and means for discontinuing the lowering of the pallet after the desired length of column has descended.

11. In a machine for making hollow concrete articles, in which such articles are formed by removing successive sections from 45 the lower portion of an intermittently descending unset cementitious column of tubular form maintained between inner and outer upright elements, in combination, an outer shaft element, an inner core element, a pallet 50 for supporting said tubular column of cementitious material, power actuated means for lowering and elevating the pallet to cause 55 the descent of the tubular column and to restore the pallet prior to the succeeding descent, and means for severing the tubular column of cementitious material and for supporting the column during the restoration 60 of the pallet.

12. In a machine for making hollow con-

crete articles, in which such articles are formed by removing successive sections from the lower portion of an intermittently descending unset cementitious column of tubular form maintained between inner and outer upright elements, in combination, an outer shaft element, an inner core element, a pallet for supporting said tubular column of cementitious material, power actuated means for lowering and elevating the pallet to cause the descent of the tubular column and to restore the pallet prior to the succeeding descent, means for severing the tubular column of cementitious material and for supporting the column during the restoration of the pallet, and means for disconnecting the pallet lowering and elevating mechanism from the source of power automatically by the movement of the parts of the machine 80 to bring the pallet to rest at such point as to produce an article of predetermined length.

13. In a machine for making hollow concrete articles, in which such articles are formed by removing successive sections from the lower portion of an intermittently descending unset cementitious column of tubular form maintained between inner and outer upright elements, in combination, an outer shaft element, an inner core element, a pallet for supporting said tubular column of cementitious material, power actuated means for lowering and elevating the pallet to cause the descent of the tubular column 95 and to restore the pallet prior to the succeeding descent, means for severing the tubular column of cementitious material and for supporting the column during the restoration of the pallet, means for disconnecting the pallet lowering and elevating mechanism from the source of power automatically by the movement of the parts of the machine to bring the pallet to rest at such point as to produce an article of predetermined length, 100 and manually actuated means for reengaging the elevating means with the source of power.

14. The method of making round concrete articles which consists in maintaining a slushy mass of concrete in a supporting upright container shaft element to unwater the concrete and compact the same into an unset cementitious column of round form, thereafter raising the supporting element to permit the unset cementitious column to protrude from the bottom and thereafter severing the protruding end of the column.

In testimony whereof I hereunto affix my signature.

ALFRED OWEN CROZIER.
